UNITED STATES PATENT OFFICE.

KURT EVERE, OF CHARLOTTENBURG, GERMANY, ASSIGNOR TO GENERAL ELECTRIC COMPANY, A CORPORATION OF NEW YORK.

INTERNAL-COMBUSTION ENGINE.

1,157,932.

Specification of Letters Patent.

Patented Oct. 26, 1915.

Application filed July 28, 1914. Serial No. 853,584.

To all whom it may concern:

Be it known that I, KURT EVERE, a subject of the King of Prussia, residing at Charlottenburg, Germany, have invented certain new and useful Improvements in Internal-Combustion Engines, of which the following is a specification.

This invention relates to internal-combustion engines and especially to that class in which a charge of air is compressed in the working cylinder to a degree of heat which suffices to ignite a charge of fuel injected thereto. Such engines are provided with governors which regulate the amount of fuel injected so that the energy produced will be just enough to carry the load. When the load is reduced or perhaps thrown off entirely, the heat developed by compression may not be sufficient to ignite the fuel, owing to its absorption by the cooling jacket and to the relatively greater chilling effect of the blast air when only small charges of fuel are admitted. It is hardly practicable to have the compression in the working cylinder so high that even at no load the fuel is ignited, because this would give excessive pressures and temperatures at intermediate and full loads.

The object, therefore, of my invention is to obtain a good ignition at all times irrespective of the variation in load, and this is accomplished by increasing the charge of air when the engine output decreases. This method of operation compensates for the lessening of the heat of combustion when small amounts of fuel are supplied, and corrects any tendency toward irregularity in ignition.

Various means may be employed for effecting the result above set forth, but the preferred mode is by means of a by-pass connecting the two ends of the scavenging pump cylinder, and an automatic controlling device for said by-pass responsive to changes in the amounts of fuel fed to the engine cylinder.

In the accompanying drawings, Figure 1 is an end elevation of a combined blast and scavenging pump for a two-cycle high compression combustion engine equipped with my regulator, which is shown partly in section; Fig. 2 is a cross-section of the scavenging pump and regulator, and Fig. 3 is a vertical section of the same.

The blast-air portion of the pump is of

the multi-stage type, having a first stage piston 1 and a second stage piston 2. The scavenging pump piston 3 is of large diameter, working in a cylinder 4 which has ports 5 and 6 at its ends. Atmospheric air is admitted to these ports by a valve 7 actuated by a link 8 and other connections to an eccentric (not shown) on the shaft 9. The air reaches the valve through a silencer 10. The pump delivers into a chamber or receiver 11, which communicates with the scavenging ports of the engine cylinder 11a.

Adjacent to the cylinder 4 is a tube 12, communicating with the ends of the cylinder and containing a valve. The tube is preferably inclosed in a chamber 13, which communicates by a port 14 with the lower end of the cylinder 4. The upper end of the tube passes through the upper end of the chamber and communicates by a port 15 with the upper end of the cylinder 4. A plurality of ports 16 in the tube put the ports 14 and 15 into communication, so that the structure forms a by-pass connecting the ends of the scavenging pump cylinder. In 80 the tube slides a piston throttle valve 17 controlling the ports 16. In order to open and close this valve and thus by-pass more or less of the air compressed by the scavenging pump, and consequently decrease or 85 increase the amount of air delivered to the engine cylinder under varying load conditions, I provide connections between this valve and the speed governor of the engine. A convenient mode of carrying out this feature of the invention is shown in the drawings and will now be described.

The engine is equipped with a fuel pump, which has a variable delivery regulated by the speed governor. In the drawing there 95 is shown a double-barreled pump having an actuating lever 18 pivoted on a floating fulcrum 19 which moves up and down as the load on the engine decreases and increases respectively. In order to place the throttle 100 valve 17 under control of this moving element, a lever 20, secured to a rock shaft 21, is pivotally connected with the floating fulcrum 19. The rock arm 22 on said shaft 21 is connected by a link 23 to the piston 105 valve 17.

The operation is as follows: When the load on the engine decreases, the speed governor causes the floating fulcrum 19 to rise, reducing the amount of fuel delivered to the 110

- engine cylinder. The floating fulcrum carries up with it the end of the lever 20, thereby causing the throttle valve 17 to reduce the effective opening of the ports 16. The 5 by-pass being throttled, more of the scavenging air is forced into the engine cylinder, so that the compression will be greater and the increased heat developed will be sufficient to ignite the lessened charge of fuel. 10 This operation occurs automatically, and the quantity of scavenging air delivered to the cylinder will vary exactly in inverse ratio to the load, maintaining correct ignition conditions at all times. 15 In accordance with the provisions of the patent statutes, I have described the principle of operation of my invention, together with the apparatus which I now consider to represent the best embodiment thereof; but 20 I desire to have it understood that the apparatus shown is only illustrative, and that the invention can be carried out by other means.
- What I claim as new and desire to secure 25 by Letters Patent of the United States, is,—
1. The combination with an internal-combustion engine of the high compression type in which fuel and scavenging air are separately admitted to the cylinder, of means 30 for automatically increasing the charge of scavenging air as the load decreases, and vice versa, in order to maintain stable ignition conditions.
  2. The combination with an internal-combustion engine of the high compression type, in which the fuel and scavenging air are separately admitted to the cylinder, of a 35 governor responsive to the load on the engine, means controlled by the governor for regulating the charge of fuel directly with the load on the engine, and means controlled by the governor for regulating the amount

of scavenging air supplied to the cylinder in inverse ratio to the load on the engine.

3. The combination with an internal-combustion engine having a scavenging pump, 45 of means for automatically varying the amount of scavenging air delivered to the engine cylinder in inverse ratio to the load 50 on the engine.

4. The combination with an internal-combustion engine having a scavenging pump, 55 of a by-pass for said pump, and means for automatically controlling said by-pass in accordance with the load on the engine.

5. The combination with a two-cycle internal-combustion engine having a scavenging pump, of a by-pass for said pump, a 60 throttle valve for the by-pass, and means for automatically opening and closing said valve as the load on the engine increases 65 and decreases respectively.

6. The combination with a two-cycle internal-combustion engine having a scavenging pump, of a by-pass for said pump, a 65 throttle valve for the by-pass, and connections between said valve and the speed governor of the engine.

7. The combination with a two-cycle internal-combustion engine having a scavenging pump, of a by-pass for said pump, a 70 throttle valve for the by-pass, a fuel pump delivering variable quantities of fuel to the engine cylinder in accordance with variations in load, and connections between a 75 variable element of said pump and said valve.

In witness whereof, I have hereunto set my hand this 10th day of July, 1914.

KURT EVERE.
